UNITED STATES PATENT OFFICE.

JACKSON ROBINSON, OF PITTSBURG, PENNSYLVANIA.

FURNACE-DOOR.

975,892.

Specification of Letters Patent. Patented Nov. 15, 1910.

Application filed May 14, 1910. Serial No. 561,298.

To all whom it may concern:

Be it known that I, JACKSON ROBINSON, a citizen of the United States of America, residing at Pittsburg, in the county of Allegheny and State of Pennsylvania, have invented certain new and useful Improvements in Furnace-Doors, of which the following is a specification, reference being had therein to the accompanying drawing.

10 This invention relates to furnace doors, and the objects of my invention are to provide a furnace with a door that will withstand the intense heat to which the same is subjected, and to provide novel means for 15 cooling the door whereby it cannot warp or become distorted.

Other objects of my invention are to provide a concrete furnace door that can be easily manufactured at a comparatively 20 small cost, and to attain the above objects by a door that is simple in construction, durable, easy to handle and highly efficient for the purposes for which it is intended.

With the above and such other objects in view as may hereinafter appear, the invention consists of the novel construction, combination and arrangement of parts to be hereinafter specifically described and then claimed.

30 Reference will now be had to the drawing forming a part of this specification, wherein:—

Figure 1 is a front elevation of a door in accordance with my invention, Fig. 2 is a 35 rear elevation of the door, Fig. 3 is a vertical sectional view of the same, and Fig. 4 is a horizontal sectional view of the door in a doorway.

A door in accordance with my invention 40 comprises a rectangular body 1 of concrete or other plastic material that can be molded in a suitable mold to form the structure. In the rectangular body 1 there is embedded a plurality of pipes 2 for the reception of a 45 cooling medium. The pipes 2 are disposed in a U-shaped manner and are connected together by elbows 3 with the upper ends of the vertical pipes protruding from the top of the door. The pipes are located in proximity to the vertical edges of the door and to the bottom edge thereof, and one end of the pipe is provided with a flexible connection 4, as a tube, to admit water or another cooling agent to the pipes, while the other 55 exposed end is provided with connections 5 and a flexible connection 6, as a hose for the

outlet of water, the water being circulated through the pipes 2 during the operation of the furnace.

The inner side of the body 1 is shaped to 60 provide a rectangular recess or pocket 7 for fire-brick 8 or other non-fusible material, the fire-brick being exposed to the heat at the doorway 9 of a furnace 10. The fire-brick 8 adjacent to the lower edge thereof 65 is provided with a peep opening 11 longitudinally alining with a similar opening 12 formed in the body 1, and pivotally mounted, as at 13 upon the front side of the body 1 is a shutter 14 adapted to close the 70 outer end of the opening 12, said shutter having a suitable handle 15.

In the front side of the body 1 adjacent to the vertical edges thereof are staples 16 adapted to receive hooks or other fastening 75 means 17 carried by the front side of the furnace body 1 adjacent to the doorway 9, these hooks retaining the door within the doorway.

Mounted in the upper front edges of the 80 body 1 are straps 18 and connected to these straps are hoisting chains or cables 19 adapted to move the door out of the doorway 9 whereby the contents of the furnace can be drawn.

While in the drawing there is illustrated a preferred embodiment of the invention, it is to be understood that the structural elements thereof can be varied or changed, as to the size, shape and manner of assemblage 90 without departing from the scope of the appended claim.

Having now described my invention what I claim as new, is:—

A furnace door comprising a unitary rectangular concrete body having its inner face provided with a relatively rectangular recess surrounded by a relatively wide marginal portion, said body further provided at its lower end with a peep opening, an 100 elongated shutter pivoted at its upper end to the outer face of said body and having an enlarged lower end for closing said opening, a handle connected to the shutter for shifting it, means for conducting a cooling 105 medium through the bottom and side marginal portions of said body, said means opening through the top of said body at each end thereof, an insert formed of rows of fire brick completely filling said recess 110 and having the exposed face thereof flush with the marginal portions of the inner face

of said body, said insert formed with an aperture registering with the peep opening of the body, means for supplying and withdrawing a cooling medium to and from said 5 conducting means, straps connected to said body for coupling it to an elevating and lowering means, and staples projecting from the outer face of the body and adapted to

receive fastening means for retaining the door in position.

In testimony whereof I affix my signature in the presence of two witnesses.

JACKSON ROBINSON
